FRANZ LÖSEL, OF BRUNN, CZECHOSLOVAKIA.

STEAM TURBINE POWER PLANT AND SYSTEM.

Application filed August 15, 1924; Serial No. 732,307, and in Austria September 24, 1923.

This invention relates to steam turbine power plants and systems, particularly plants including multistage steam turbines.

The object of the invention, generally stated, is a novel power plant or system having a considerable reserve capacity and having peculiar flexibility of operation which renders it capable of economical working under varying load conditions. The invention is particularly applicable to power plants having multistage steam turbines and resides in such division of the turbines into such parts and so connected up with steam supply and separate condenser units that all of said parts may be either connected in at full load or partial load operation, or one or more parts may be entirely disconnected at partial load and smaller output from the steam supply so as to obtain maximum efficiency in the turbine parts remaining in service and without undue losses in the idle turbine part or parts which continue to run. More particularly the invention includes a two or more part multistage turbine unit connected at stages of different pressures in such manner with two or more condenser units and with two or more separate steam supply lines leading to stages of different pressures of said turbine unit that either the high pressure part of the turbine or a lower pressure part of the turbine unit may be simultaneously operated by receiving steam from the two or more supply lines. My improved power plant or steam turbine system particularly includes a separate special condenser provided for higher pressure stages of the turbine unit and connected with the exhaust of a high pressure stage of the high pressure part of the turbine unit and a lower pressure steam supply boiler unit connected to an intermediate stage of the turbine unit with connections such that all parts of the turbine unit and the two or more boiler units may be connected in and run simultaneously or the turbine unit may be divided at will to run from separate steam lines simultaneously or to run one divided part independently of the other and without regard to whether the latter is receiving steam energy or supplying power to the shaft.

Another important object is to permit independent operation of any section with-

out interfering with the operation of the remaining section. 55

Other objects and advantages will herein-after appear.

For a better understanding of the invention, reference may be had to the accompanying drawing which is a schematic or 60 diagrammatic illustration of a power plant embodying my invention.

Referring to the drawings, I have indicated diagrammatically as an illustrative form of the invention a multistage turbine unit mounted on and driving a common shaft a , this turbine unit comprising a high pressure part h , an intermediate pressure part m and a lower pressure part n . It is understood that each of these parts h , m and n may be divided into a number of turbine stages and particularly it is preferable that the turbine parts h and m should be back pressure parts of the multistage low velocity character. Connected with the admission end of the high pressure part h of the turbine unit is a boiler unit k_1 giving any suitable steam pressure supply as p_1 and a steam line with a valve means r is indicated for supplying the steam from the boiler k_1 to the admission end of the high pressure turbine part h . Similarly there is a boiler unit k_2 which is capable of supplying steam at a pressure p_2 which is lower than the pressure p_1 , namely a pressure corresponding to the 70 pressure of the steam admitted to the intermediate part m of the turbine. A steam line containing a valve means t is indicated for supplying the steam from the boiler k_2 at, say, pressure p_2 to the admission end of the 75 turbine part m . The system includes a main condenser c_1 connected with the exhaust end of the low pressure turbine part n for creating the necessary vacuum operation. C_1 indicates a second and separate special condenser connected through a steam line and valve means u with the exhaust end of the 80 high pressure turbine part h for a purpose hereinafter set forth, and the two turbine parts h and m are connected through a valve 85 means s .

The boiler or steam generator k_2 , therefore, supplies the steam at pressure p_2 which is consumed only in the turbine parts m and n while the steam supply from the high 90 pressure boiler k_1 may be used in all three 95

parts h , m and n by progressive expansion therethrough (valve u closed) or merely in the first or high pressure part h when the valve s is closed and valve u open. The steam generator k_1 is provided essentially for the supply of high pressure steam to the turbine part h and thence by expansion through m , n during the normal working. While the boiler k_1 is supplying steam for all three turbine parts, which ultimately exhausts into the main condenser c_2 , the valves u and t are closed and the valves r and s are open. The plant may, however, be divided into two separate units by opening the valves u , t and r and closing the valve s , namely the unit k_1 , h and c_1 and the unit k_2 , m , n , and c_2 and either of these parts may be operated independently of the other if desired from its particular source of steam. In the event of operation of the high pressure division the condenser c_1 takes the back pressure steam from the exhaust end of the high pressure part h and condenses the steam in the manner of the usual condenser, either under vacuum or under pressure, as is desired, but in any event at a pressure which is slightly lower than the exit pressure of h . At partial or reduced loads a peculiarly economical operation is effected by shutting off entirely one of these divided parts. For example, if the load can be carried by the intermediate and low pressure parts m and n then the valves r and s may be closed with the valve u open, which shuts the high pressure part h off from its supply of steam from the boiler k_1 and by the connection of the exhaust end of the high pressure part with the separate condenser c_1 , the high pressure turbine part h may be caused to run in a vacuum or back pressure without doing work and with a consequent minimum loss if the condenser remains in operation. Similarly, if desired, the intermediate and low pressure parts m and n may be shut off by closing the valves s and t and opening the valves r and u , thereby causing the parts m and n to run in a vacuum with a minimum of losses if the main condenser remains in operation. The special condenser c_1 serves the purpose of receiving the exhaust steam from the high pressure stages of the part h when it is running independently and it may also be used to cause the latter to run in a vacuum with a minimum of losses when the parts m and n are supplying the reduced load from the low pressure boiler system k_2 . But for independent operation of the high pressure part h and the lower pressure parts m and n of the turbine unit it becomes very important to employ two or more separate condensers to obtain a perfectly independent operation of the different parts of the combined system, to prevent the operation of the system from being affected

and to maintain reliability of operation. According to the present invention, these advantages are secured by providing, in addition to the main condenser c_2 , a separate special condenser c_1 for the higher pressure stages and to supply thereto the exhaust fluid from such higher pressure stages or part during certain periods of operation. The separate condenser c_1 takes care of the condition of the exhaust fluid from the high pressure part h independent of the back pressure or vacuum and the temperature conditions in the main condenser c_2 . The back pressure and temperature conditions in the main condenser c_2 and in the separate condenser c_1 may be different but by application of this invention interference of one with the other is avoided. This is particularly important because the temperature and pressure of the exhaust fluid of the high pressure turbine part h are in most cases considerably higher than the back pressure and temperature of the exhaust fluid of the low pressure part n . This is obvious inasmuch as the exhaust fluid of the high pressure part h acts during certain periods of operation of the turbines as the admission fluid or a part of the admission fluid for operating the intermediate part m and low pressure part n of the turbines. The exhaust conditions of the exhaust fluid correspond in such cases more or less to the admission conditions of the intake fluid of the succeeding turbine part n . Therefore, by the provision of the separate condenser c_1 , which also takes account of the higher pressure and temperatures of the exhaust fluid of part h , positive provision is made for preventing harmful interference with the temperature and the back-pressure or vacuum conditions in the main condenser and consequently for preventing harmful and dangerous effects in the low pressure turbine part n which would result from such temperature and pressure changes in the main condenser c_2 . The independence of the main condenser from the higher pressure system and from the conditions therein and further the independence of certain parts of the system and their independent and simultaneous operation as well as their dependent cooperation are secured by the present invention. In certain instances it may be desirable to supply steam simultaneously from both boiler units k_1 and k_2 , in which case both valves r and t also valve s would be opened and valve u closed. When the divided parts of the plant are running independently valve u is opened and valve s closed. The parts m , n must therefore be capable of receiving and consuming both the steam from the exhaust part h and the steam supplied from boiler unit k_2 and any of the usual and well known valve means (indicated generally by the letter t) may be employed for admitting and regulating the

supply of steam thereto according to the varying demand. While I have diagrammatically indicated the independent turbine parts *h*, *m* and *n* as connected with a common drive shaft, it is understood that each of said turbine parts may have its own shaft and that in certain cases mechanical couplings may be disposed between the parts to effect mechanical connection and disconnection between them when they are to be connected together or one of them is to be used separately.

Having thus described my invention, what I claim and desire to protect by Letters Patent is:

1. In a steam turbine power plant the combination of a multistage steam turbine unit divided into two or more independent parts operating at different pressures and connected in tandem to successively receive the expanding steam, said turbine parts driving a common load shaft, a pair of independent steam generators for generating steam at different pressures, the high pressure steam generator having a steam connection leading to the admission end of the high pressure part and the low pressure steam generator having a connection leading to the admission end of a lower pressure part of the turbine unit, a main condenser unit connected with the exhaust of the lowest pressure part of the turbine unit, a separate condenser unit provided for higher pressure stages of the turbine unit and adapted to be connected with the exhaust of a higher pressure turbine part, and valve means in the connections leading from the steam generators to their respective turbine parts and in the connections leading respectively from

the exhaust end of the higher pressure part 40 to the second condenser and to the admission end of the following part of the turbine.

2. In a steam turbine power plant, the combination of a multistage steam turbine unit divided into at least two independent 45 parts operating at different admission pressures and adapted to be operated in series, a steam generator for generating high pressure steam and another steam generator for generating steam of a lower pressure than 50 said high pressure steam generator, a steam supply connection leading from said high pressure steam generator to the admission end of the high pressure turbine part, a 55 steam supply connection leading from said lower pressure steam generator to the admission of a lower pressure stage of said turbine unit, a main condenser for said turbine unit, an exhaust connection line leading from the lowest pressure part of said turbine unit to 60 said main condenser, a separate condenser provided for higher pressure stages of the turbine unit, a connection between said separate condenser and the exhaust of the high 65 pressure turbine part of said turbine unit, valve means in the last-mentioned connection, and valve means in said connections leading from said steam generators to their respective turbine parts and also in the connection leading from the exhaust of the high 70 pressure stage of said high pressure turbine part to the admission of said following part of the turbine for opening and closing the connections.

In testimony whereof, I have signed my 75 name to this specification.

FRANZ LÖSEL.
